HENRY D. JEFFREY AND JACOB LIVER, OF WINONA, MINNESOTA, ASSIGNEES TO THEMSELVES, CALVIN A. BIERCE, AND FRANK B. HOLBROOK, ALL OF SAME PLACE.

BOB-SLEIGH.

SPECIFICATION forming part of Letters Patent No. 337,586, dated March 9, 1886.

Application filed October 7, 1885. Serial No. 179,238. (No model.)

To all whom it may concern:

Be it known that we, HENRY D. JEFFREY and JACOB LIVER, of Winona, in the county of Winona and State of Minnesota, have invented a new and useful Improvement in Bob-Sleighs, of which the following is a full, clear, and exact description.

Reference is to be had to the accompanying drawings, forming a part of this specification, in which similar letters of reference indicate corresponding parts in all the figures.

Figure 1 is a plan view of the forward bob of a bob-sleigh, the bolster being omitted, the king-bolt shown in section, and the tongue broken away. Fig. 2 is a sectional side elevation of the same taken through the broken line *xx*, Fig. 1. Fig. 3 is a rear elevation of a part of the same enlarged, the runner and raves being shown in section and part of the cap being broken away. Fig. 4 is a sectional plan view of the knee taken through the line *yy*, Fig. 3, and showing a part of the runner. Fig. 5 is a bottom view of the cap, the arms of the clip-bows being shown in section.

The object of this invention is to provide bob-sleighs constructed in such a manner that the knees will form double-acting connections between the runners and beams, and will thus allow the sleighs to work easily, while forming a firm, substantial, and durable support for the beams.

A further object of this invention is to keep the front beam always in an upright position, make the draft of the rear bob come directly upon the tongue, and allow the reach to be used with a loose coupling.

The invention consists in the construction and combination of various parts of a bob-sleigh, as will be hereinafter fully described and then claimed.

A represents the runners, to the forward ends of which are pivoted the ends of the roller *B* of the tongue *C*.

To the runners *A* are attached plates *D*, upon which rest the lower ends of the knee-standards *E*, the bodies of which are made oval in form, and have grooves in their front and rear sides to receive the raves-pins *F*, that keep the said standards in place. The raves-

pins *F* pass up through the runners *A*, and 50 their heads are countersunk in the faces of the said runners, as indicated in dotted lines in Figs. 2 and 3, and are covered by the runner-shoes *G*. The upper ends of the raves-pins *F* pass through holes in the raves *H*, the middle parts of which rest in recesses *I*, formed to receive them in the upper ends of the standards *E*. The end parts of the raves *H* are inclined downward, and their ends are secured to the runners *A* in front and rear of the 55 knee-standards *E* by bolts *J*, clips, or other suitable means. The standards *E* are made hollow, as shown in Fig. 4, to allow them to have a suitable size and strength without being 60 too heavy.

Upon the outer and inner sides of the upper ends of the standards *E* are formed arms *K*, the upper sides of which are rounded and slightly tapered from their inner ends toward their outer ends.

Upon the upper side of the arms *K* rest concave bearings, formed in the lower sides of the caps *L*, so that the said caps *L* can rock upon the said arms *K*, while the taper of the said arms allows the said caps to have a 75 lateral play. The outer ends of the arms *K* are of less width than the ends of the bearings in the caps. This construction allows of the horizontal oscillation as well as the vertical rocking movement of the tapered arms in the 80 said bearing, so that a universal joint is obtained.

The standards *E* and caps *L* are connected with each other and with the beam *M* by clips, the bows *N* of which rest in grooves in 85 the lower sides of the outer ends of the arms *K*, and in recesses in the lower edges of the lugs *O*, formed on the lower parts of the sides of the caps *L*. The arms of the bows *N* pass along grooves in the sides of the caps *L*, pass 90 through holes in the beam *M*, and through holes in the yokes *P*, and have nuts *Q* screwed upon their upper ends.

Upon the lower sides of the middle parts of the caps *L* are formed projections *R*, the 95 bottoms of which are rounded, and which fit into the recesses *I* and rest upon the raves *H*, so as to take the strain from the arms *K*.

and give an easier lateral movement to the caps L. With this construction the caps L can rock upon the arms K and raves H, so that the beam M can remain stationary, while 5 the runners A incline upward or downward in passing over uneven ground. With this construction also the caps L can have a lateral movement upon the arms K of the standards E, so that one of the runners A can 10 move a little in advance of the other, which freedom of movement greatly facilitates the starting of the sleigh when heavily loaded. Another advantage of this construction is that when heavily-loaded sleighs have to be drawn 15 out of or into the road to pass other sleighs, or for other purposes, the runners can be turned at an angle of about twenty-five degrees (25°) without wrenching or twisting the load, so that the loaded sleigh can be turned to one or 20 the other side with ease.

To the rear end of the tongue C is secured, by a belt, S, or other suitable means, the forward end of the chain T, the rear end of which is secured by a link or clevis, U, and 25 the king-bolt V, or other suitable means, to the beam M. The king-bolt V pivots the bolster to the beam M in the ordinary manner, which bolster is not shown in the drawings, as there is nothing new in its construction or operation. By this construction the draft of the 30 rear bob will come directly upon the tongue and not upon the beam, front roller, runners, clips, and the joint-connection between the beam and runners, thus leaving the joint perfectly free from all strain, except the weight 35 of the load upon it; and the beam will be kept always in an upright position, and cannot tip backward, as is the case with ordinary oscillating bob-sleighs in which the draft comes 40 upon the front roller, runners, oscillating joint, and beam, and tips the said beam to the rearward, and is liable to bend or break the said king-bolt or the reach. This construction also 45 allows the reach to be attached to the front bob with a loose coupling, which cannot be done on an oscillating sleigh when the chain T is not used.

Having thus fully described our invention, we claim as new and desire to secure by Letters Patent—

1. The combination, with the knee E, having the transverse rounded arms K, having a longitudinal recess, I, and tapering outward slightly from said recess, of cap L, having a

projection, R, on its under side fitting within 55 the recess I, and concavities on opposite sides of the said projection to receive the upper rounded and tapered surfaces of the arms K, the said concavities being of greater width than the tapering arms, whereby a rocking 60 and a lateral movement is afforded, substantially as and for the purpose set forth.

2. The combination, with the cap L, provided on its under side with the projection R, rounded recesses tapering outward from opposite sides of said projection, and recessed depending lugs O on opposite sides of the ends of the said recessed parts of the knee E, having a longitudinal recess, I, on its top, rounded arms K, tapered outward from opposite sides 70 of said recess and resting in the recesses of cap L, the recesses being of greater width than the tapering arms, the clips N, fitting in the recesses of lugs O, and holding the cap and knee together, substantially as set forth. 75

3. The combination, with the knee E, having the longitudinal recess I and the rounded outward tapered arms K on opposite sides of said recess, of the rave H, resting in the bottom of recess I and bent downward at opposite 80 sides thereof, the cap L, provided with the projection R, fitting in recess I and resting on the rave H, the cap being recessed to receive the arms K and rock and oscillate laterally thereon, substantially as set forth. 85

4. The combination, with the runners A and the cross-beam M, of the knees E, having longitudinal recesses I, and rounded outward tapered arms K on opposite sides of said recesses, the rave-bolts extending upward from the runners in front and rear of the knees E, the raves H resting between their ends on the bottoms of the recesses I, apertured to receive the upper ends of the rave-bolts, and bent therefrom downward and secured to the runners, 95 the caps L, having central projections, R, resting on the raves within the recesses I, rounded recesses receiving the arms K, and grooved lugs O on opposite sides of the ends of said grooved portions, and the clips N, passed upward through the grooves in said lugs and secured to the beam M, substantially as set forth. 100
